United States Patent Office.

JOHN L. BURCH, OF FRANKLIN, TENNESSEE.

Letters Patent No. 67,493, dated August 6, 1867.

IMPROVED SPLINTS.

The Schedule referred to in these Letters Patent and making part of the same.

TO ALL WHOM IT MAY CONCERN:

Be it known that I, JOHN L. BURCH, of Franklin, in the county of Williamson, and State of Tennessee, have invented a new and useful Improvement in Splints for Surgical Use in Cases of Injured Limbs; and I do hereby declare that the following is a full, clear, and exact description of the same, reference being had to the annexed drawings, making part of this specification, in which—

Figure 1 is a perspective view, and

Figure 2 is a horizontal section.

The same letters are employed in both figures in the indication of the same parts.

The object of my invention is to furnish sets of splints which may be adjusted to the injured limb, and adapted to either the right or left leg, which will sufficiently confine the injured limb without unnecessarily impairing the action of the parts. I have shewn in the drawings a set of splints adaptable to use in case of a leg broken below the knee, or to the case of a sprained ankle.

Strips of wood, as shown at A, are prepared of the proper length, and permanently bent to fit the form of the limb. On each of these is attached a series of metallic plates, B, riveted to the splint above and below, but curved or otherwise so formed as to permit a strap, C, to be passed around the leg between the plates and splints. These straps are fastened upon the leg by buckles. The first splint put upon the strap rests against the buckle; the last one put on is fastened by a small screw passing through the plate B. The first and last ones, A¹ and A², are shorter than the others, being cut off below the lower strap and above the foot. Those coming on the sides and back of the leg extend below the heel. The space in front of the leg between the splints A¹ and A² is occupied by the wide splint D, which rests against the pad D', placed between it and the leg. The sole E is attached to the splints by a thong, E', which passes through eyes in the bottom of the sole and through metallic loops, B', formed by plates on the end of the splints, and by the hooks G, which are fastened to the sole and hooked over the thong E' between the splints at the hinder end of the sole. Straps F are attached to the sole under the ball of the foot, and pass across the foot, crossing one another on the instep, and are fastened by buckles to each end of the strap F', which is fastened to the middle splint. By tightening and loosening these straps respectively the foot may be turned to one side or the other, as desired.

In order to change the splints from use on one leg to use on the other, the screws in the splint A¹ are removed and the splints taken from the straps. They are then replaced upon the straps in the reverse order, the splint A¹ being put on first and A² last. To vary the splint according to the size of the limb, the splints nearest the end splints A¹ and A² may be omitted or added.

What I claim as my invention, and desire to secure by Letters Patent, is—

1. The mode substantially as herein described of constructing and arranging the reversible splints A, A¹, A², and of attaching the same to the injured limb.
2. The combination of splints A, A¹, A², and D, respectively, constructed substantially as set forth.
3. In combination with the vertical splints, the adjustable sole E attached thereto and to the foot, substantially as described.

In testimony whereof I have signed my name to this specification in the presence of two subscribing witnesses.

JOHN L. BURCH.
